UNITED STATES PATENT OFFICE.

WILLIAM F. GRASSLER, OF WILLIAMSPORT, PENNSYLVANIA.

BOILER-FURNACE.

SPECIFICATION forming part of Letters Patent No. 331,492, dated December 1, 1885.

Application filed May 11, 1885. Serial No. 165,070. (No model.)

To all whom it may concern:

Be it known that I, WILLIAM F. GRASSLER, a citizen of the United States, residing at Williamsport, in the county of Lycoming and State of Pennsylvania, have invented certain new and useful Improvements in Boiler-Furnaces, of which the following is a specification, reference being had therein to the accompanying drawings.

10 This invention relates to certain new and useful improvements in steam - generating boiler-furnaces; and it has for its objects, first, to provide a boiler with means for deflecting the smoke and gaseous products of combustion and the attendant sparks and cinders in their course to the smoke - flues, for introducing atmospheric air into the furnace, and for injecting steam into the furnace and mingling it with the gaseous and solid particles of combustion, whereby the escape of smoke and all products of combustion, as well gaseous as solid, from the stack while the engine is not laboring under steam is effectually prevented; second, to provide a boiler with 15 means for deflecting the smoke and gaseous products of combustion and the attendant sparks and cinders in their course to the smoke-flues, for introducing atmospheric air into the furnace, for injecting steam into the furnace and mingling it with the gases and solid products of combustion, and for moderating the ordinary violent sucking action of the exhaust-steam upon the fuel in the fire-box, whereby the same end as that above set 20 forth is accomplished, whether the engine is steaming or not.

25 In the accompanying drawings, forming a part of this specification, and on which similar letters of reference indicate the same or corresponding features, Figure 1 represents a longitudinal vertical sectional view through a locomotive-boiler, showing the several features of my invention in connection therewith; Fig. 2, a transverse vertical sectional view of 30 such a boiler on the line $x x$ of Fig. 1; Fig. 3, a detached enlarged sectional view of a portion of one of the jacket-pipes, showing the steam-injecting tube and sprayers in elevation; Fig. 4, a detached vertical sectional view of 35 one of the sprayers; Fig. 5, a plan view there-

of; Fig. 6, a front view of the furnace-door, and Fig. 7 a detached plan view of one of the draft-pipes and the yoke-bar.

The letter A designates a locomotive-boiler of any approved type, the same being provided with the usual smoke-flues, B, the smoke-box C, and the furnace or fire-box D. This fire-box is surrounded by the usual water-legs, E, and is provided with a door-opening, F.

The letter G indicates the door, which is hinged to the boiler in any approved manner, and is provided with apertures H and serrations I. A bolt, J, passing through an aperture in the door, serves to receive and support a regulating-plate, K, which fits within the recessed outer face of the door proper, and is provided with apertures L and a spring-catch, M. By rotating this plate the size of the apertures in the door may be regulated so as to admit the desired influx of atmospheric air into the fire-box, the catch M, engaging with the serrations I, serving to fix the position of the said plate. A disk, N, is secured to the door by means of rods O, and is slightly smaller in diameter than the door F, the function of which is to cut off the direct inflow of cold air upon the fire, and to suspend the air, as it were, within the doorway until it becomes partially heated, and then to distribute it into the fire-box in a thin film.

The letter P designates a deflector, preferably constructed of fire-brick, and of arched form, located within the fire-box and extending from wall to wall laterally, and in a longitudinal direction from the front wall to a little more than half-way to the rear wall. This deflector is supported preferably by means of screw-studs Q, screwed into the walls of the fire-box, as more clearly seen in Fig. 2. The position of the deflector with respect to the door-opening is preferably such as to deflect the incoming air down toward the mass of fuel, and this whether the door is closed and the air coming through the apertures or opened and the air passing directly through the door-opening. This deflector also prevents the smoke and gaseous products of combustion and the sparks and cinders from rushing directly to the flues under the influence of the draft and suction created by the exhaust-

steam, this retardation thus serving to hold these products, &c., in the fire-box a longer time before they reach the flues, and giving opportunity for them to be consumed. Again, 5 the deflector acts to concentrate the heat toward the upper rear portion of the fire-box, through which portion the smoke, gaseous products, and cinders are compelled to pass in their passage to the smoke-flues, thereby 10 subjecting them not only to the general heat of the fire-box, but to this intensified heat due to concentration. As the heat thus deflected passes upward by the door additional oxygen is supplied, and by reason of the disk N it 15 becomes warmed, and is then injected in a film form. The arch is slightly cut away at P', in order to allow such small solid particles of the products of combustion as may pass over the deflector to roll down and return to the bed of 20 fuel. It is found in practice that there is no tendency of the smoke or gases to pass through this aperture, as the draft of the flues at this point is comparatively weak.

I shall now refer to the devices which act 25 to moderate the violent sucking action of the exhaust-steam upon the fuel.

The letter R designates the exhaust-nozzle, which may be of any approved form. Extending from and around this nozzle a short 30 distance within the smoke-stack is a perforated pipe, S, preferably of conical form, the perforations being, by preference, in the form of slots, and disposed so that those of one row slightly lap those of the next row. The function 35 of this pipe is to conduct the exhaust-steam from the exhaust-nozzle to the stack and to moderate the sucking action of that steam upon the fire. This latter branch of its function is effected through the instrumentality 40 of the slots, which, while they permit the exhaust-steam to create a partial vacuum in the smoke-box, and thereby induce a sucking action upon the particles of combustion in the fire-box, also lessen or moderate its action. 45 It is found, however, that these slots, being small and numerous, so distribute the sucking action of the exhaust over the entire surface of the pipe S that this action becomes somewhat dissipated. To counteract this effect 50 and concentrate the sucking action at different points around the said pipe, I provide the draft-pipes T and U, each of which is provided with a flaring skirt. The pipe T is provided with one or more rows of slots, one row being 55 preferably in the upper hood, and being larger than the slots in the moderating-pipe S. Both the draft-pipes T and U are adjustably connected together, in the present instance by means of brackets W, secured to the pipe T, 60 and bolts X, passing through slots in the pipe U. These draft-pipes are maintained in position in the smoke-box by means of the yoke-bar Z, as more clearly seen in Fig. 7, the ends of which yoke are connected with the walls of 65 the smoke-box.

As above intimated, the function of the hoods is to subdivide the sucking action of

the exhaust-steam and to concentrate the force of the subdivisions at different points along the moderating-pipe. The lower hood acts 70 upon these flues immediately below, opposite, and above it, while the space between it and the upper end of the draft-pipe U and the crown of the smoke-box allows the exhaust-steam to act through the upper rows of flues. 75 The object in adjusting the draft-pipes T and U with respect to each other is to properly distribute the action of the exhaust.

I have ascertained by actual trial that when the throttle-valve is open and the engine is 80 laboring, and the exhaust-steam is passing through the moderating-tube, the combustion is so perfect as to consume not only the small solid particles which are ordinarily drawn through the smoke-flues in the shape of 85 sparks and cinders, but also to consume the smoke and gaseous products. During such time there is an entire failure of the smoke to pass out of the stack, and this result I consider attributable to the joint action of 90 the deflector and the influx of atmospheric air and the moderated action of the exhaust-steam upon the fuel. It is found, however, that when the throttle-valve is closed and the engine is in motion as a consequence of its momentum, 95 and is not laboring under the influence of the steam, the smoke escapes from the stack, if the fuel is comparatively fresh in the fire-box. The engine, when the fuel is fresh, also smokes if standing. In this case, however, 100 as also in the case when it is in motion, but not under the influence of steam, the combustion is still so perfect as to consume the sparks and cinders which ordinarily escape. It is to consume and get rid of the smoke under the conditions just named when the exhaust-steam is 105 not in action that I provide the device now about to be described.

The letter a designates the metallic jacket-pipes, each of which is entirely closed at one 110 end and provided at the other with a plug, b, having a projecting threaded nipple, which engages a threaded aperture in the wall of the fire-box, whereby communication between the water-legs and the interior of these pipes is 115 established. The object of this water communication is twofold,—first, to protect the jacket-pipes from burning out under the action of the extreme heat incident to their position, and, second, to jacket or protect the 120 steam-injecting pipes c against like destruction, the said steam-injecting pipes c connecting at one end with any suitable part of the boiler, preferably with the steam-dome, in the present instance by a short section, d, having 125 a T-coupling, e, and a three-way cock, f, whereby the admission of steam into the pipe c is controlled. The section d preferably extends within the cab, so as to present the three-way cock within reach of the engineer. From 130 the section d the pipes c extend in any convenient direction to the sides of the fire-box, and thence pass through the outer and inner walls and into the jacket-pipes a. Each injecting-

pipe is provided with a series of steam distributors or sprayers, which extend through the walls of the jacket-pipes and into the fire-box. These sprayers consist of the nipples *g* and the tips *h*, having a tapering interior and a slotted orifice at the end, whereby the steam is sprayed into the fire-box in thin sheets, which spread and so intermingle with each other as to virtually form one sheet of steam across the fire-box, which acts to intercept the exit of the smoke and other products of combustion, the heat decomposing the steam and converting it into its constituent gases, (oxygen and hydrogen,) and thus forming a combustible substance, which, uniting with the smoke, &c., is consumed.

It will be observed that a space is left between the opposite ends of the jacket-tubes. This is done in order to allow of the expansion and contraction of these pipes. To fill this space with steam, the ends of the injecting pipes are also provided with sprayers, which extend through the ends of the jacket-pipes.

25 When the throttle-valve is closed, the engineer is to admit steam into the injecting-pipes and set the sprayers to work, which, as above stated, act in lieu of the exhaust-steam. If desirable, the sprayers may of course be at 30 work during the time that the engine is under the influence of steam; but this is not necessary.

While the admission of air through the door assists the deflector and moderating-pipe in bringing about an effectual consumption of the products of combustion, as above stated, this result I have found by practice may be reached without the aid of the door having the openings.

40 This invention is designed especially for locomotive - engines; but it is applicable to any boiler without departing from the spirit of my invention.

I have also found by actual trial on the road 45 that I am able to use a larger exhaust-nozzle, which has the effect of freeing the steam more quickly, thereby destroying or greatly reducing the back action in the cylinders. As a consequence of this fact, the full force of the 50 steam admitted into the cylinders is secured. This fact, and that of the perfect combustion

which I obtain, greatly reduces the consumption of the fuel.

The matter herein shown and described but not claimed forms the subject of another application filed by me on the 4th day of September, 1885.

Having thus fully described my invention, what I claim as new, and desire to secure by Letters Patent, is—

1. In a boiler - furnace, the combination, with the fire-box and an inclined deflector located therein, of steam-injectors located at or near the upper end of the deflector and disposed so as to throw a film of steam across the remaining upper portion of the fire-box, whereby the escape of the products of combustion to the smoke-flues is intercepted.

2. In a boiler - furnace, the combination, with an air-inlet for the fire-box, and a deflector located therein, of the jacket-pipes and the steam-injecting tubes having sprayers and communicating with the boiler.

3. In a boiler - furnace, the combination, with the fire-box and an air-inlet door having a distributing-plate and an inclined deflector located therein, of the jacket-pipes and the steam - injecting tubes having sprayers and communicating with the boiler.

4. In a boiler - furnace, the combination, with the fire-box and an inclined deflector therein, of jacket-pipes and steam-injecting tubes having sprayers and communicating with the boiler.

5. In a boiler - furnace, the combination, with the fire-box, of the jacket-pipes communicating with the water-legs, and the steam-injecting tubes communicating with the boiler extended into the said pipes and provided with sprayers projecting into the fire-box.

6. In a boiler - furnace, the combination, with the fire-box, of the jacket-pipes communicating with the water-legs and having a space between their inner ends, and the steam-injecting tubes having sprayers and communicating with the boiler.

In testimony whereof I affix my signature in presence of two witnesses.

W. F. GRASSLER.
